WINDOW

Roger W. Eisinger, Washington, D. C.

Application April 1, 1943, Serial No. 481,475

10 Claims. (Cl. 20—42)

1

This invention relates to windows with frames and sash parts formed of wood, metal, plastics or other suitable material, and particularly to windows for dwellings, hospitals, nurseries, offices, barracks, temporary buildings and the like.

It is the general object of the present invention to provide a novel and improved glazed window of extremely simple construction and operation, which uses a minimum of lumber or other materials and which can be constructed without the use of any critical hardware except a few fastening elements, and even these can be eliminated by the use of waterproof glue.

One of the principal purposes of my invention is to provide a window at low cost and offering the advantages of minimum material, improved ventilation, draft elimination, simplicity of construction, ease of installation and operation, improved vision and facility for cleaning and screening.

An important object of the invention consists in the provision of a window of simplified form and construction and including a center sash of half frame height more or less, together with top and bottom sash each of quarter frame height more or less and normally positioned, when closed, in the same plane with the center sash, provision being made for adjusting the center sash if desired and either or both small sash to varying degrees of overlap with the larger sash whereby simultaneous or independent top and bottom ventilation may be obtained.

Another important object of the invention consists in the provision of a small bottom sash adapted to be normally positioned in the plane of the center sash, having a cooperating wind and weather stop with the sill providing a pivot about which the sash can be tilted inwardly at the top to act as a ventilator, provision being also made whereby this sash can be lifted in a plane parallel to the center sash to adjusted overlapping positions therewith.

An important feature of the invention resides in the provision, on the movable sash, of laterally slidable members capable of being manually positioned in vertical grooves in the frame to provide weather stops when the sash is closed, to wedge the sash against the outer or blind stop and which may also serve to position the sash in tilted ventilator or lifted positions in respect to the frame.

Other and further objects and features of the invention will be more apparent to those skilled in the art upon a consideration of the accompanying drawings and following specification, wherein are disclosed several exemplary embodiments of the invention, it being understood that such changes in and combinations of the various embodiments may be made as fall within the scope

2

of the appended claims without departing from the spirit of the invention.

In said drawings:

Fig. 1 is an inside elevation of a window constructed in accordance with the present invention, certain portions of the frame being broken away to more clearly illustrate important features thereof;

Fig. 2 is a vertical central section on an enlarged scale, taken on line 2—2 of Fig. 1 and showing the sash in the closed position in solid lines and in dotted lines illustrating the movable sash in partially opened positions.

Fig. 3 is a fragmentary horizontal section 15 through one side rail of the center sash and a portion of the frame taken on the line 3—3 in Fig. 1;

Fig. 4 is a view similar to Fig. 3, on an enlarged scale, and sectioned on line 4—4 of Fig. 1 through the upper movable sash;

Fig. 5 is a view similar to Fig. 4 but taken on line 5—5 of Fig. 1 and illustrating the upper movable sash with its adjuster shown locking the same in closed position;

Fig. 6 is a fragmentary section similar to Fig. 4 but showing a modified weather stop;

Fig. 7 is a view similar to Fig. 6 showing a further modification in the adjustable weather stop;

Fig. 8 is a fragmentary vertical section of a modified construction showing the manner in which the adjustable weather stop on the lower sash serves to hold the same in several adjustable ventilating positions;

Fig. 9 is a view similar to Fig. 8 but showing the lower sash completely removed to illustrate the grooves for receiving the weather stop;

Fig. 10 is a vertical section through a modified form of window showing the bottom sash closed, and, in dotted lines, partially raised to illustrate a construction of weather stop serving also the function of holding the window in adjusted open positions;

Fig. 11 is a front elevation of a fragment of the right side of the window of Fig. 10 with the frame in section in the plane of the weather stop groove;

Fig. 12 is a fragmentary perspective view illustrating the combined weather stop and adjustable positioning means of Figs. 10 and 11; and

Fig. 13 is a fragmentary horizontal section on broken line 13—13 of Fig. 11.

At the present time there is a serious threatened shortage of suitable windows for war-time construction of low cost housing, temporary office and military buildings, hospitals, nurseries and the like, the primary cause being the lack of critical metals for hardware, sash weights and similar accessories. A careful study of the problem 60 of meeting the shortage indicates a requirement

for extreme simplification of window structures for the purposes enumerated, which will not only eliminate the need for hardware but which will reduce the demand for labor for installation and lumber or other materials for construction, both of which are also scarce. In the solving of the problem a window has been provided which makes use of a simple plank frame adapted for brick, masonry or frame structures and which requires a minimum of mill work for its construction and assembly.

The window may be said to differ materially from the conventional double hung windows or casement windows in that it is composed of three independent sash, one above the other, all in the same plane when closed, and in which the center sash is preferably fixed and of a height equivalent to one-half more or less of the frame height. All of the sash are preferably glazed with a single pane, thus providing a large central picture window uninterrupted in the line of sight by the conventional meeting rails of the double hung window. The top and bottom sash are each of one-fourth frame height more or less so that when opened by overlapping the center sash, an area of one-half of the frame opening is exposed for ventilation, thereby achieving equally as good results in ventilation area as the double hung window. Since the open area, however, is divided into two portions, one at the very bottom and the other at the very top, ventilation is materially improved. Moreover, either the top or the bottom section alone can be opened to any desired degree. In addition, the bottom sash is arranged so that it can maintain its position on the sill while its top is tilted inwardly to various adjusted positions, whereby it acts as a ventilator, permitting an opening of varying size with substantially a zero component of vertical height so that any air entering is deflected upwardly and is not annoying to the occupants of the room and will not blow papers and other light objects from furniture at approximately the height of the sill.

The top and bottom sash can be completely removed, when desired, to facilitate their cleaning, leaving the center sash in fixed position with the outside accessible for cleaning through the openings left by the removal of the small sash.

Referring now to the drawings, for a better understanding of the invention it will be seen that the window includes three sash 10, 11 and 12, each glazed with a single pane, the first and third of which are approximately of one-quarter height of the frame opening, while the second is one-half of the frame height. The sash are made in any desired style with suitable top, bottom and side rails, but because of the relatively small size of the movable parts and the preferred fixed condition of the main portion can be made of lighter lumber than is conventional and yet be subject to no more distortion or warping.

The frame is of the simplest possible construction and may be conveniently termed a "plank" frame, comprising a flat top member 15, flat side member 16, and a simple sill member 17 of somewhat heavier lumber, downwardly sloped for water drainage from a line at the intersection of the inner plane of the sash frame to the outer edge. Inside of the sash the sill may be planed off until it is substantially level as at 18 to act as a substitute for the usual stool. The top and side members of the frame are of the same width, an amount equivalent to the thickness of the studs 19, sheathing 20, lath and plaster 21, in a conventional frame structure into which they fit

with the utmost simplicity. The inside trim is preferably of the simple sanitary mold type comprising side members 22 and a top member 23 mitered together at the corners as shown. The sill member 17 is somewhat wider than the overall width of the trim and receives an apron 24 extending beneath the square lower ends of the side trim members 22.

As seen in Fig. 4 each side member 16 is beaded on its outer edge as at 25 to receive and form a water tight connection with an outside frame member 26 of small size and simple form against which the clapboard 27 abuts as seen in Fig. 2.

The inner edge of the frame at the outside of the window is rebated as at 28 to receive the blind or outside stop 30 in the form of a rectangular strip of conventional construction arranged to be overlapped by the outside frame 26 as clearly seen. All three sash members, when closed, bear closely against this outside stop whereby they are rendered relatively weather-tight.

As seen in Fig. 3 the side rail 31 of the center sash has its inner face engaged by the parting stop 32 shown as fitted in a groove 33, not greater in vertical height than the length of the center sash and held in position by several finishing nails 34. This parting stop is relatively thin as seen in Fig. 3, for reasons to be later explained.

Any appropriate means is used to fix the center sash against vertical movement. A suitable inside stop or mold 36 is shown in Figs. 2 and 4 slightly overlapping the inner edge of the trim members 22 and 23. It is spaced from the parting stop by a distance equivalent to slightly more than the thickness of the side rail of the sash and it forms with the parting stop slide troughs for the upper and lower sash which are drawn into this space before being adjusted vertically for opening the window. When the top and/or bottom sash are in one of the grooves, space is provided for sliding the main sash in its original plane. The width between frames in the plane of the grooves is greater than the plane of the sash, when closed to provide added clearance for ease in sliding (see Figs. 4 and 5).

The bottom rail 40 of the bottom sash is grooved centrally of its width in the form of an inverted U 41, as clearly seen in Fig. 2, in order to fit over a tongue or strip 42 suitably attached to the sill 17 either by being rebated into the same or attached by nails or the like. The strip forms a relatively close fit to the walls of the groove to provide a wind and weather stop and the tongue may be formed in the peculiar shape shown in the figure to have a reentrant outer side serving to return any water which might be blown up toward its top so it will drain off. This connection between the bottom sash and sill serves as a pivot about which the bottom rail of the bottom sash may swing when the sash is tilted inwardly at the top in the manner illustrated in dotted lines at 44. The sash may assume any one of a number of positions inclined to the vertical with the top drawn in, the sides maintaining a close fit with the frame.

To permit separation of the top rail of the bottom sash from the bottom rail of the center sash the two are molded as shown at 46 and to further increase the weather tightness here, a batten 47 may be secured to the lower rail of the center sash to overlap the joint as clearly illustrated. The molding line between the two sash rails is generally inclined to the horizontal so that no difficulty is experienced in swinging the

sash inwardly for ventilation purposes. In order that it may assume a substantial angle, say 30° of the vertical, a portion of the inner stop or molding 36 is cut away as at 37 with the cut being on a sharp bevel as at 38 serving to force the upper end of the sash inwardly when it is lifted as will be later described. A portion 36' of the inner stop is left in position at the bottom and provided with a beveled upper face 39 which forms a stop to limit the amount of inward movement of the sash when it acts as a ventilator.

When it is desired to open the bottom sash by straight upward lift the upper end is drawn inward slightly to clear the center sash and then the whole sash is lifted upward when it will slide in the groove between the parting stop 32 and the inner stop 36.

The upper sash is slightly less in vertical height than the distance between the top rail of the fixed sash and the top of the frame in order to leave a space 50 whereby the sash may be lifted prior to being swung inwardly to slide in the same groove occupied by the lower sash when raised. This upper sash may be termed a jump sash because of the manner in which it is lifted and then drawn in at the bottom. It is preferred to provide a watertight connection between the bottom rail of the top sash and the top rail of the middle sash, and a tongue and groove arrangement as shown at 52 is suitable for the purpose, augmented by a batten 53 secured to the lower rail of the top sash as described in connection with the junction of the lower rail of the middle sash and the upper rail of the bottom sash. The space 50 must be greater in vertical height than the amount of overlap of the batten 53 below the junction line.

A simple mechanism is preferred for holding both the upper and lower sash in their adjusted overlapping relation with the fixed center sash and for holding the center sash if the same is arranged to be adjusted. The conventional transom pin 55, such as clearly illustrated in section in Fig. 5 forms a convenient device for the purpose. This is a conventional piece of hardware and need not be described in detail. The sleeve 56 is secured in each side rail of the movable sash at a convenient location whereby the handles 57 are available for both releasing the pins and manipulating the sash. Suitable rows of holes 58 are arranged in the sides of the frame to accommodate the tips 59 of the pin, whereby the sash can be locked in any one of a number of desired positions variously overlapping the fixed center sash. The pins also serve to lock the sash in their closed positions. Obviously plain wooden dowels, loosely fitted, may be substituted for the metal transom pins.

In connection with the bottom sash, the described locking pins not only provide for holding the sash in overlapping relation to the center sash, but by virtue of an arcuately spaced series of holes 60 provides for adjustment in the ventilator positions of the sash.

When raising the upper sash to close the same or lowering the lower sash for the same purpose, it is convenient to have the arcuate guide blocks 61 and 62 arranged respectively in the top and bottom of the grooves in which the sash operate to throw the top and bottom portions, respectively, thereof into their proper position in the plane of the fixed sash.

Each of the movable sash is preferably equipped with a pair of manually adjustable weather stops

which serve to lock it tightly in closed position pressed against the blind stop 39 and provide an additional increment to the circuituous path through which the air must travel from the outside to the inside of the window. Such a weather stop is clearly illustrated in Fig. 4 at 64. It comprises a strip of wood, of the same thickness as the parting stop 32, attached by at least two fastenings or screws 65 to the inner face of a side rail of the movable sash but slidable laterally thereof by virtue of slots 66 through which the fastening means pass loosely. The inner face of each of the weather stops 64 is chamfered near the outer edge as at 67 whereby it may form a tight wedging fit and force the side member of the sash outwardly into tight engagement with the blind stop. These weather stops on the upper and lower sashes are shown in Fig. 2 as being in alignment with the parting stop 32 and above and below the same. When the two weather stops on either sash are pulled inwardly as by means of such knobs as shown at 69, they are withdrawn from their respective slots 68 and the sash can be moved. When the sash is in the closed position the weather stops are pressed outwardly and engaged tightly in the grooves 68 and the inclined wedge portions 67 force the sash outwardly against the outer stops 37 to insure against leakage and rattling.

An alternative form of such weather stop is shown in Fig. 6 where the member 64' is concealed from view in a channel 70 plowed in the vertical edge of the sash rail. In order that this form of weather stop may be actuated, it is equipped with a rod 71 projecting out through the face of the sash rail and there equipped with a convenient knob 72 serving both to actuate the weather stop and as a handle for the sash. This rod when moved laterally travels in an elongated slot 73 in the sash rail. Naturally the groove 68' with which this stop cooperates is properly positioned in respect thereto in the frame and out of alignment with the parting stop 32. This form of weather stop is substantially invisible and equally as effective as the other.

The weather stop shown in Fig. 4 is held in position by round headed screws 65, but in Fig. 7 another arrangement is illustrated wherein the screw 75 which is received in the wood of the sash has a cylindrical shank 76 passing partially through a slot in the weather stop, and this is provided with a flat filister head 77 received in the counter slot 78 in the weather stop so it is always entirely below the outer surface of the same.

In the embodiment illustrated in Fig. 8, the construction is not substantially different from the earlier described embodiments, but the locking pins such as shown in Fig. 5 are no longer made use of to hold the lower sash in any of the adjusted ventilator positions. This function is taken over by the weather stop strips 64, which it will be remembered, are laterally slidable to engage in the grooves 68, such as shown in Fig. 9, in vertical alignment with the parting stop 32. As shown in this same figure, inclined grooves 68' and 68'' radiate from the junction of the groove 31 with the sill to permit tilting of the bottom sash to several ventilator positions, making use of the weather stops to engage these inclined slots for holding the sash in place.

In Figs. 10 to 13, inclusive, is illustrated a further embodiment in which the weather stops are equipped with pins or dowels which serve to hold the sash in any of the positions to which it can

be moved. The top sash, which is not illustrated in these figures, may be similarly equipped. As shown, the bottom sash is provided with slidable weather stop strips 80 mounted in one of the manners already described, and each of these strips is provided at its outer edge with one or more wooden dowels, pegs or metal pins 81. The slot 82 into which the weather stop moves for holding the sash in closed position, has its bottom wall extended at 83 to loosely house these pins, which in this position of the sash either have no function or merely augment the weather stop for holding the sash tightly closed. When the sash is to be lifted to a position such as shown in Fig. 10, these pins 81 are adapted for cooperation with any of a plurality of holes 85 appropriately positioned in the face of the side member of the frame. No cooperating slot is necessary to assist the weather stop in positioning the window in its open positions.

In Fig. 10 the inside stop 36 is shown cut away in the manner illustrated in Fig. 2 to permit the bottom sash to be tilted to ventilator positions. For the purpose of holding the same in adjusted ventilator position appropriate arcuate series of holes 86 are provided in the frame much in the manner of the holes 60 illustrated in Fig. 2. It will be appreciated that any of the types of weather stops illustrated can be equipped with auxiliary adjusting pins for the purpose of eliminating the separate locking pins, as shown at 55. By combining the locking pins with the weather stops the operation of the movable sash is much simplified since by merely grasping the knobs 69 used for moving the weather stops the same can be released so that the sash can be moved and these knobs can then be pressed outwardly to engage the pins with the appropriate holes in the frame for fastening the sash in either the lifted or the ventilator positions. It will be appreciated that while in connection with the earlier embodiments metal transom pins have been illustrated for holding the sash in place, that these can be replaced by suitable hard wood dowels, thereby eliminating additional metal from the construction. The only metal remaining in such a window would be the screws or rods for positioning or moving the weather stops and the few nails necessary for assembling the frame and its associated parts. It is believed that by the judicious use of weather proof glue even these fastenings can be eliminated.

It will be seen that a very satisfactory solution of the problem of providing simplified windows has been made in the several embodiments illustrated.

I claim:

1. In a window of the type described, in combination, a plank frame having a sill, an outside or blind stop, a center sash one-half the height of the frame and engaging said stop, top and bottom sash against the said stop each of one-quarter frame height and receiving support respectively from the center sash and the sill, a parting stop at the top and behind the center sash only, each of the small sash having a bottom rail contoured to fit the support beneath and to provide a water and wind stop, that of the lower sash being constructed to remain tight when the said sash is tilted inwardly at the top through a substantial angle to act as a ventilator and single means to hold the lower sash in adjusted ventilator positions and in adjusted overlapping relation to the center sash.

2. In a window of the type described, in com-

bination, a plank frame having a sill, an outside or blind stop, a center sash one-half the height of the frame and engaging said stop, top and bottom sash against the said stop each of one-quarter frame height and receiving support respectively from the center sash and the sill, a parting stop at the top and behind the center sash only, each of the small sash having a bottom rail contoured to fit the support beneath and to provide a water and wind stop, that of the lower sash being constructed to remain tight when the said sash is tilted inwardly at the top through a substantial angle to act as a ventilator, and means to hold the lower sash in adjusted ventilator positions, said last mentioned means including laterally movable weather stops on the lower sash.

3. In a window of the type described, in combination, a plank frame having a sill, an outside or blind stop, a center sash one-half the height of the frame and engaging said stop, top and bottom sash against the said stop each of one-quarter frame height and receiving support respectively from the center sash and the sill, a parting stop at the top and behind the center sash only, each of the small sash having a bottom rail contoured to fit the support beneath and to provide a water and wind stop, that of the lower sash being constructed to remain tight when the said sash is tilted inwardly at the top through a substantial angle to act as a ventilator, means to hold the lower sash in adjusted ventilator positions, and means to hold each of the small sash in adjusted overlapping relation to the center sash, said last mentioned means comprising laterally movable weather stops engaged with the frame members.

4. In a window of the type described, in combination, a plank frame, an outside or blind stop, a center sash one-half the height of the frame opening and engaging said stop, a parting stop behind the center sash, a bottom sash fitting against the blind stop when closed and having a water and wind tight connection with the center sash and with the bottom member of the frame, the latter connection forming a hinge for the lower sash when tilted inwardly at the top to act as a ventilator, means to secure the lower sash in adjusted overlapping relation to the middle sash and in engagement with said parting stop, a top sash fitting against the blind stop when closed and having a water and wind tight connection with the middle sash, and means to secure the top sash in adjusted overlapping relation to the middle sash and in engagement with said parting stop, said securing means for the top and lower sashes including laterally movable weather stops thereon.

5. In a window of the type described, in combination, a frame having an outside stop, a half height sash in the middle of said frame against said stop and backed by a parting stop, top and bottom quarter height sash against said outside stop and adapted for sliding inside of the parting stop, an inside stop to guide said movable sash, said inside stop being absent adjacent the upper portion of the lower sash whereby the same may be tilted inwardly to act as a ventilator, the side rails of the lower sash each being fitted with a laterally slidable weather stop strip, the frame having cooperating grooves to receive said strips when the sash is closed to lock and weatherproof the same.

6. In a window of the type described, in combination, a frame having an outside stop, a half

75

height sash in the middle of said frame against said stop and backed by a parting stop, top and bottom quarter height sash against said outside stop and adapted for sliding inside of the parting stop, an inside stop to guide said movable sash, said inside stop being absent adjacent the upper portion of the lower sash whereby the same may be tilted inwardly to act as a ventilator, the side rails of the lower sash each being fitted with a laterally slidable weather stop strip, the frame having cooperating grooves to receive said strips when the sash is closed to lock and weatherproof the same, means to manually withdraw said strips and inclined grooves to receive said strips when the sash is tilted to retain it in position.

7. In a window of the type described, in combination, a plank frame, a blind stop, a center sash of at least one-half frame height engaging said blind stop, top and bottom sash engaging said stop when closed and each of not more than one-quarter frame height, the top sash being of the jump type, means to hold the top sash in adjusted overlapping relation to the center sash, the bottom sash being adapted to tilt inwardly at the top or to be raised in overlapping relation to the center sash, a concealed wind and weather stop between the frame sill and the bottom rail of the bottom sash, said last mentioned stop acting as a hinge when the sash is tilted, and single means for holding said bottom sash in any adjusted tilted or raised position.

8. In a window structure, a plank frame, a blind stop on said frame, a jump sash adapted when closed to abut said stop, laterally movable weather stop strips on said sash, grooves in said frame to receive said strips when the sash is closed, manual means to withdraw or extend said strips, a pin projecting outwardly from the outer edge of each strip and a series of holes in the

frame side members to receive the said pins to hold the sash in adjusted open positions.

9. In a window structure, a plank frame, a blind stop on said frame, a jump sash adapted when closed to abut said stop, said sash being arranged to be drawn inwardly for sliding adjustment in a plane parallel to its closed plane, each side bar of said sash having a cooperating, laterally slidable weather stop strip, the side frame members being grooved to receive the edges of said strips when extended with the sash in closed position, each of said strips having a laterally extending pin, and each frame side member having a plurality of holes to selectively receive a pin 15 to hold the sash in an adjusted sliding position.

10. A window as claimed in claim 9 in which the sash can also be tilted to act as a ventilator, and additional holes to receive said pins to hold the sash in adjusted ventilator positions.
